DESIGN FOR A KNIFE HOLDER

Horner H. Hopkins, Des Moines, Iowa

Application March 6, 1939, Serial No. 83,386

Term of patent 7 years

To all whom it may concern:

Be it known that I, Horner H. Hopkins, a citizen of the United States and resident of Des Moines, Polk County, Iowa, have invented a new, original, and ornamental Design for a Knife Holder, of which the following is a specification, reference being had to the accompanying drawing, forming a part thereof:

Fig. 1 is a front perspective view of the knife holder, showing my design;

Fig. 2 is a side elevational view;
Fig. 3 is a rear elevational view; and
Fig. 4 is a top plan view thereof.

I claim:

The ornamental design for a knife holder, substantially as shown.

HORNER H. HOPKINS.
